DISPENSING AND STORAGE CABINET FOR
EFFERVESCENT BEVERAGES

Otto J. Vincent, Seattle, Wash.

Application April 30, 1936, Serial No. 77,227

2 Claims. (Cl. 312—140.1)

My present invention relates to improvements in the beverage dispensing apparatus art and more particularly to a dispensing and storage cabinet for effervescent beverages.

This present invention is of that present type of apparatus which, in a compact, self-contained unit provides elements which have been found by experience to be necessary if effervescent beverages, such as beer, are to be handled with the minimum waste and if they are to be delivered in the best possible condition.

Distinguishing my present equipment from that already to be found on the market, are certain features that add to the convenience, workability and appearance of the unit and more particularly to those items which provide an arrangement such that commercial units may be used and still provide a compact cabinet where the, ordinarily, heavy beer kegs can be handled, old ones withdrawn and new ones supplied, with the minimum of effort and annoyance. These features consist essentially in providing a hinged beer tray that swings upwardly so as to provide ample working room for the insertion of fresh kegs of beer and the removing of emptied ones with their tap rods in place. My cabinet is further provided with a construction that permits the removal or replacement of a beer keg without any interference from cross members which, normally, lie across the upper portion of the keg entry opening. This further facilitates the handling of kegs and saves a great deal of time which is particularly desirable when the units are placed in busy places.

While providing these desirable features my cabinet still performs the essential services expected in equipment of this type, namely, refrigerating units to cool the beer itself as it is drawn, to maintain the beer kegs at the desired low temperature and, further, to permit the use of standard beer dispensing equipment to the end that full advantage may be taken of the many desirable features found in such devices.

Other and more specific objects will be apparent from the following description taken in connection with the accompanying drawings, wherein

Figure 1 is a perspective view showing a cabinet made after the teachings of my invention, in which the doors to the keg compartment are shown open and the beer tray is shown in its raised position.

Figure 2 is a vertical-sectional view through my cabinet with the tray raised and the doors open.

Figure 3 is a view similar to Figure 2, except it is in fragmentary form and shows the doors closed and the tray in its normal position for use.

Referring to the drawings, throughout which like reference characters indicate like parts, 10 designates the cabinet top, which may be used as a serving bar in which case it is provided with the usual perforated drainage tray 12 having the drain connected with the overflow of the cabinet. 10 In certain instances it may be desirable to have top 10 of such a height that it will slide in under the normal bar used. At the right end of the cabinet as shown in Figure 1 I provide a compartment 14 having the usual facilities for cold storage and bottled goods and in its lower portion provided with the usual compressor and refrigerating unit as is common with this type of equipment.

The beer keg and tray compartment which 20 comprises the novel features of this device consists of the usual floored portion 16 adapted to properly support kegs of beer, as 17. Means are provided to take care of two kegs as is common with this type of equipment. The novelty 25 resides, however, in having the central post 18, to which doors 20 and 21 engage when in their closed position, supported in a novel manner by having a substantially horizontal support member 22 which is secured to the back of the 30 cabinet and extends out to support the upper end of post 18. As a matter of convenience I find it desirable to give this the general shape of a triangular frustum to the end that maximum 35 rigidity may be secured, and further that it may serve other useful purposes such as providing a secure anchoring means for the overflow or drain piping 24. Doors 20 and 21 are hingedly mounted on the usual offset hinges 26 and are secured by self actuating latch members 28. 40

The beer tray 30 of my cabinet is hingedly secured to the cabinet as at 32 and is adapted to swing upwardly after the showing of Figure 2. When the tray is in its uppermost position I provide a conveniently disposed prop member 34 45 which is pivotably secured at 35 to tray 30. This prop member engages support 22 when the tray is in its raised position and holds the same securely in its raised position so that it will not interfere with the movement of the beer kegs. 50

To provide security and prevent tray 30 from being raised, except when desired, I provide a downwardly extending stop member 36. This stop is adapted to engage in the rabbeted top 38 of doors 20 and 21. The stop 36, in the form 55

of a rib rigid with the bottom face of the tray is spaced, slightly, back of the front bottom edge of the tray to provide a front groove, and the rabbets 38, 38 of the two doors form grooves that are alined when the doors are closed. The rib 36 is substantially the length of the combined lengths of the two rabbets, so that when the doors are closed and latched with the tray in closed position, the rabbets fit into the groove 10 of the tray and the stop fits into the groove of the doors, and the frictional engagement of the rabbets against the stop firmly holds the tray against opening movement. To provide adequate sealing I provide a yieldable gasket at 40, between 15 the doors and the tray.

Tray 30, following the principles embodied in the majority of beer trays, is arranged to drain to one point and, at this point, a drain 42 is provided. This in my present cabinet is adapted to engage, when it is in its operative position, the opening 44 of drain pipe 24 and thus adequately take care of any spillage or flushing that may occur.

My cabinet is provided with the usual beer 25 cooling coils which are not illustrated, and also keg cooling coils 46 which are in turn cooled by the refrigerating plant contained in compartment 14. To further assist in maintaining the cool 30 temperature desired, I line my cabinet with heat insulation material as at 48 and provide the usual step doors of considerable thickness as 20 and 21.

Method of operation

In using my equipment the principal advantage 35 is the ease with which kegs can be removed or replenished. There are two features, particularly, in my cabinet which make this most convenient. In removing a keg from my cabinet the first operation is to open doors 20 and 21. This will release, and make it possible to raise, tray 30 to the position indicated in Figures 1 and 2. It is then possible for the operator to disconnect the tap rod at 50 from the fixed piping 52 of the cabinet. The keg can then be rocked and twisted 45 until it is brought out from under tray 30. To facilitate this, however, there should be considerable clearance between the bottom of the tray and the top of the tap rod equipment. This I have indicated in Figures 2 and 3 by the broken line 50 54. As soon as the keg has been taken entirely out of the cabinet, the tap rod and its assembly can then be removed from the keg and be inserted in a filled keg outside of the cabinet. Then, 55 following in reverse order the operation described, the keg with its tap rod properly seated can be placed into its normal position of use, where its tap rod can then be connected with the service piping 52. During this entire oper-

ation it has been only necessary to swing tray 30 upwardly to its position as shown in Figures 1 and 2, and it is not necessary, as in many other types, to lift the heavy, bulky tray entirely out of the cabinet. Further, there is no danger of spilling in this cabinet during this period of the operation as the back of the tray is still under the discharge nozzle 56, thus protecting the entire cabinet from becoming unsanitary as so often happens where effervescent liquids, particularly 10 beer, are spilled in inaccessible places where it is not convenient to wipe the same up again. As soon as the beer keg has been put in place and the tap rod connected, tray 30 can be lowered to the usual position, for such trays, as shown in 15 Figure 3 and the device is ready for service. It is desired to point out that were a conventional arrangement used, in which the center post 18 is connected to the sides of the cabinet as by securing a bar between post 18 and the posts 20 upon which hinges 26 are secured, it would not be possible to take the keg and its tap out as a unit and the structure shown would not result.

The foregoing description and the accompanying drawings are believed to clearly disclose a 25 preferred embodiment of my invention but it will be understood that this disclosure is merely illustrative and that such changes in the invention may be made as are fairly within the scope 30 and spirit of the following claims.

I claim:

1. The combination in a beverage dispensing cabinet having an open front, a center-post at the front of the cabinet, and an elevated horizontal support rigid with the post and cabinet, with a pair of oppositely opening hinged doors, of a tray extending substantially the combined width of the two doors and hinged to the cabinet above the doors, a prop pivoted on the cabinet adapted to rest on the support for holding the tray in open position, a stop-rib mounted on the under face of the tray, and rabbets on the upper edges of said doors for frictional engagement with the stop-rib when the tray and doors 45 are closed.

2. The combination with an open-front cabinet having a center-post, and a pair of oppositely-opening hinged-doors, of a tray extending substantially the combined width of the two doors and hinged to the cabinet above the doors, a stop-rib mounted on the under face of the tray to form a front edge-groove, and rabbets forming a complementary groove at the upper edges of the doors, whereby frictional engagement of the rabbets against the stop-rib holds the tray against opening movement when the tray and doors 55 are in closed position.

OTTO J. VINCENT.
